(57) **CLAIM**

The ornamental design for a hooded sweatshirt, as shown and described.

DESCRIPTION

FIG. 1 is a perspective front view of a hooded sweatshirt showing my new design;

FIG. 2 is a front elevational view thereof;

FIG. 3 is a rear elevational view thereof;

FIG. 4 is a left side elevational view thereof; and,

FIG. 5 is a right side elevational view thereof.

The broken lines depict portions of the hooded sweatshirt that form no part of the claimed design. The broken lines showing the zipper, drawstrings, seams, and stitching form no part of the claim.

1 Claim, 5 Drawing Sheets
